DESIGN FOR AN EVISCERATING TOOL FOR FOWLS OR THE LIKE

Edward M. Lynn, Chicago, Ill.

Application February 9, 1944, Serial No. 112,529

Term of patent 14 years

(Cl. D11—1)

To all whom it may concern:

Be it known that I, Edward M. Lynn, a citizen of the United States, residing in the city of Chicago, county of Cook, and State of Illinois, have invented a new, original, and ornamental Design for an Eviscerating Tool for Fowls or the like, of which the following is a specification, reference being had to the accompanying drawing, forming a part thereof.

In the drawing:

tool for fowls or the like embodying my new design.

Figure 2 is a side elevation of the same with a portion of the handle broken away for convenience of illustration.

I claim:

The ornamental design for an eviscerating tool for fowls or the like, substantially as shown.

EDWARD M. LYNN.
